UNITED STATES. PATENT OFFICE.

CLIFFORD W. MARSH, OF BRIDGEPORT, CONNECTICUT.

PAPER SEPARATOR FOR TYPEWRITERS.

Application filed January 8, 1923. Serial No. 611,221.

To all whom it may concern:

Be it known that I, CLIFFORD W. MARSH, a citizen of the United States, residing at Bridgeport, county of Fairfield, State of Connecticut, have invented a new and useful 5 Paper Separator for Typewriters, of which the following is a specification.

This invention relates to typewriting machines and especially to the means for feeding and supporting the work sheets and transfer material for the writing operation.

In the ordinary operation of writing letters on the typewriter where one or more carbon copies are desired a great deal of 10 time is lost in interleaving the work sheets with the carbon paper and then setting the sheets in the machine preparatory to the writing operation. Further time is also lost in separating the sheets after the writing 15 operation is completed. Furthermore in the use of carbon sheets of substantially the same size as the work sheets there is danger of soiling the work sheets in the handling as the fingers of the operator are soiled by the 20 carbon paper, and if erasures are necessary considerable time is lost in advancing the work sheets and transfer paper to a position where a card may be inserted beneath the transfer paper to prevent smudging of 25 the carbon copy during the erasing operation.

The present invention has for an object, therefore, the provision of means whereby the loss of time involved in interleaving the 30 work sheets with the carbon or transfer paper, assembling them together and inserting them in the machine may be greatly reduced, and whereby the work sheets may be assembled in the machine for writing with 35 a minimum expenditure of time and effort.

It is also an object of the invention to provide mechanism in which in the ordinary writing operation there is no handling of the carbon or transfer paper by the operator required, so that soiling of the fingers and the resultant soiling of the work sheets 40 is eliminated, and also one in which a considerable saving of carbon paper or transfer material is obtained.

It is a further object of the invention to provide a device of this character in which the operation of making erasures is facilitated.

With the foregoing and other objects in

view, I have devised the novel mechanism 65 illustrated in the accompanying drawings, in which

Fig. 1 is a front elevation of the device in the position it will normally occupy when in use on a typewriter, the end members of 70 the ordinary reciprocating carriage of the typewriter being shown in section.

Fig. 2 is a transverse section through the device and also the usual work sheet support and guiding means carried by the carriage.

Fig. 3 is a similar view of the elements immediately adjacent the platen, but on an enlarged scale, and

Fig. 4 is a top plan view of the separator 75 element showing it in the position it occupies in respect to the guide rollers carried by the typewriter carriage.

In these drawings I have not illustrated the specific mechanism of the typewriter as 80 it is that of the standard typewriter. I have however, indicated at 10 the top of the typewriter frame and at 11 the reciprocating carriage ordinarily employed to carry the platen and the work sheets. This carriage 85 is reciprocated in the usual manner by any desired type of reciprocating mechanism, not shown, controlled by the operation of the keys of the typewriter. In Fig. 2 I have shown at 12 a type bar in the position for 90 making an impression. Carried by the carriage 11 is the usual curved guide plate 13 extending under the platen and having openings 14 and 15 therethrough for the guide rollers 16 and 17 adapted to press the work 95 sheets against the platen so that the sheets will be advanced to writing position upon rotation of the platen in the usual manner. These elements so far described are the standard elements now employed generally 100 on typewriters of this type.

The end bars of the carriage 11, as shown in Fig. 1, have bearings 18 and slidable securing caps 19 for rotatably securing a platen, which platen in this specific structure 105 shown may be easily removed by lifting the same from these bearings after the securing caps or slides 19 have been retracted by any suitable means such as the knob 20 in a manner well known. My invention comprises preferably a rotatable platen 21 similar to the ordinary platen having bearings 110 22 adapted to seat in the bearings 18 of the

carriage 11, the same as the ordinary platen, and has hand knobs 23 at its opposite ends for manual rotation in adjusting work sheets the same as the ordinary platen, but of course other types of platens may be employed if desired. This platen is also preferably provided with the same type of toothed ratchet wheel 24 adapted to coact with the ordinary ratchet, not shown, to give the proper line spacing. This platen is also mounted in a frame comprising end members 25 and 26, preferably of sheet metal, connected together by another plate 27, and the platen rotates in bearings in these plates. Extending longitudinally across the front of the platen is a strip of carbon paper or transfer material 28 of suitable width, but preferably relatively narrow or substantially the same width as the ordinary typewriter ribbon indicated at 29. This transfer strip is held so that it extends longitudinally of the platen at the forward side thereof on the line of writing and between the original copy ribbon and the platen. This strip of transfer material is preferably made of considerable length and wound on a supply drum or reel 30 carried by the end member 26 from which it leads over an inclined guide 31 across the front of the platen around a second inclined guide 32 and to the reel or drum 33 carried by the other end plate 25 on which the used transfer strip may be wound. A hand knob 34 may also be provided on this reel for manual operation of the same in adjusting a transfer strip. I also provide means for advancing this transfer strip automatically upon rotation of the platen, and provide for this purpose a gear 35 on the platen meshing with an idler gear 36 carried by the end wall 25 and meshing with another gear 37 having driving connection with the reel 33. This driving connection should be a one way connection so that the reel will be rotated only in a direction to wind up the transfer paper upon rotation of the platen in a direction to advance the work sheets. It should not rotate the reel upon rotation of the platen in the opposite direction. I have not illustrated this connection specifically as it may be any ordinary and well known drive such as a pawl and ratchet. I also preferably provide a spring 38 bearing against the supply reel 30 to yieldingly retard the rotation thereof and thus maintain the transfer strip taut across the front of the platen. The pressure of this spring may be adjusted by the nut 39.

Secured to the end members 25 and 26 and extending between the same is a curved guide plate and separator 40, and it is curved so as to extend closely adjacent the surface of the platen at the under side thereof, as shown in Figs. 2 and 3. This plate terminates at the front side of the platen adjacent

the lower edge of the strip of transfer material but preferably extends a slight distance above this lower edge and on the side towards the platen, as shown in Figs. 2 and 3. At the rear of the platen it includes a substantially flat portion 41 extending upwardly between the platen and the rear wall 27. This plate or separator is also provided with openings 42 and 43 for the guide rollers 16 and 17 respectively. This separator plate is so positioned that when the platen is mounted within the bearings 18 in the end walls of the carriage 11 and the rear wall 27 rests against the upwardly extending rear portion 13' of the guide plate 13 it will lie between the curved portion of this plate and the platen, as shown in Figs. 2 and 3, and the guide rollers 16 and 17 will be in alignment with the openings 42 and 43 respectively, so that this separator will not interfere with the operation of these rollers when pressing the work sheets against the surface of the platen. At the forward side of the platen are also the usual holding clips 44 carried by the carriage 11 and provided with the usual rollers 45 yieldingly pressed against the work sheets to hold them against the platen.

In operation a pair of work sheets, designed for the original and manifold copies 46 and 47 respectively, after being superposed are inserted in the machine by passing their lower edges between the platen and the roller 17 but on opposite sides of the upwardly extending rear part 41 of the separator 40, as shown in Fig. 3. Rotation of the platen in the direction of the arrow in the usual manner will feed these sheets forwardly around the platen as in the ordinary typewriter, the rollers 16 and 17 holding these sheets against the surface of the platen in the usual manner. At other times, however, these sheets are held separated by the separator or guide plate 40, and as the transfer strip 28 is a substantial continuation of this separator the two sheets of paper are guided to opposite sides of this transfer strip and the outer sheet 46 will be guided by means of the usual guide plate 48 carried by the carriage to the under side of the original copy ribbon 29. It will thus be apparent that the two work sheets are now in position for writing and that the usual carbon copy will be made with the original.

It will also be apparent that no interleaving of the work sheets with the transfer paper or handling of this transfer paper is required in setting up the work sheets, and there is practically no more trouble in setting up a plurality of work sheets to give a carbon copy in addition to the original or ribbon copy than is required in the ordinary machine after the sheets have been interleaved. As the transfer strip extends throughout the entire length of the platen

and is always on the line of writing no attention has to be paid as to whether the transfer paper is of a proper size for the work sheets, and so there is no danger of 5 omitting part of the original copy from the carbon copy. Also there is no wastage of transfer material as the entire strip is used on its passage across the front of the platen.

It will further be apparent that when 10 erasures are necessary, by merely rotating the platen a certain amount to advance the line of writing beyond the transfer material these erasures may be made without interfering with the transfer material in any way, 15 or without the necessity of placing a card beneath the transfer material to prevent smudging of the copy during the erasing operation. Also that at the completion of the writing operation there is no transfer sheet 20 interleaved with the work sheets, and there is, therefore, no time lost in separating them.

It will be still further apparent that the device is very simple in construction and that it is as easily applied to and removed 25 from the machine as is the ordinary platen. Furthermore the platen 21, the frame comprising elements 25, 26 and 27, the reels and supports for the transfer material 28, and 30 the work sheet separator and guiding element 40, 41, constitute a complete carrier unit which, after the ordinary platen has been removed from the machine, may be substituted therefor and will take the place thereof, the platen of the carrier unit being 35 mounted in the supports for the ordinary platen.

I have illustrated and described the invention as constructed to provide a single carbon copy in addition to the original or 40 ribbon copy so have used a single separator 40, but it will be apparent that one or more additional carbon copies may be secured by increasing the number of separators and strips of transfer material.

45 I have also illustrated and described the invention as constructed to provide a curved guide plate and separator 40 and 41 on the underside of and adjacent to the platen but said separator guide may extend any distance on the lower face of the platen from 50 the lower edge of the transfer material.

I have also shown the separator and guiding means as applied to a platen carrier unit but said means may be applied to any 55 platen.

Having thus set forth the nature of my invention, what I claim is:

1. The combination with the printing devices of a typewriter having a reciprocating 60 mechanism, of a carrier comprising in combination as a unit, a platen, means for carrying transfer material at one side of said platen, a separator arranged to direct work sheets to the opposite sides of the transfer 65 material, and means to removably connect

said carrier unit with said reciprocating mechanism.

2. The combination with the printing devices of a typewriter having a reciprocating mechanism, of a carrier comprising in combination as a unit, a rotatable platen, means for carrying one or more strips of transfer material transversely to the direction of rotation of said platen, and means to separate and direct work-sheets into a copying relation with said transfer material, and means to removably connect said carrier unit with 70 said reciprocating mechanism. 75

3. The combination with the printing devices of a typewriter having a reciprocating mechanism, of a carrier comprising in combination as a unit, a platen, means for supporting a strip of transfer material at one side of the platen, a separating and guiding means arranged to direct individual work sheets to the opposite sides of the transfer material, means for feeding the transfer material longitudinally of the platen, and means to removably connect said carrier unit with 80 said reciprocating mechanism. 85

4. The combination with the printing devices of a typewriter having a reciprocating mechanism and means to removably connect a platen with said reciprocating mechanism, of a carrier removably connected with 90 said reciprocating mechanism and comprising in combination as a unit, a platen, means for supporting transfer material at one side of said platen, and a separating and guiding means arranged to direct individual work sheets to the opposite sides of the transfer material. 95

5. The combination with the printing devices of a typewriter having a reciprocating mechanism and means to removably connect 100 a platen with said reciprocating mechanism, of a carrier adapted to be removably connected with said reciprocating mechanism and comprising in combination as a unit, a platen, means for supporting a strip of transfer material at one side of said platen, a separating and guiding means arranged to direct individual work-sheets to the opposite sides of the transfer material. 105

6. The combination with the printing devices of a typewriter having a reciprocating mechanism and means to removably connect a platen with said reciprocating mechanism, of a carrier adapted to be removably connected with said reciprocating mechanism by said connecting means and comprising in combination as a unit, a platen, means for supporting a strip of transfer material at one side of said platen, a separating and guiding means arranged to direct individual work sheets to the opposite sides of the transfer material, and means for feeding the 110 115 120 125 130

transfer material in a direction transverse to the direction of feed of the work sheets.

7. The combination of the printing devices of a typewriter having a carriage, means on said carriage to removably connect a rotary platen with said carriage, and guide means carried by the carriage adapted to coact with the platen to feed a plurality of individual work sheets to writing position, of a carrier adapted to be removably connected with said carriage by said platen securing means and comprising in combination as a unit a rotatable platen adapted to coact with said guide means, means for supporting a strip of transfer material at one side of the platen, and a separator at one side of the platen arranged to direct the individual work sheets to opposite sides of the transfer material.
- 20 8. The combination of the printing devices of a typewriter having a carriage, means on said carriage to removably connect a rotary platen with said carriage, and guide means carried by the carriage adapted to coact with the platen to feed a plurality of individual work sheets to writing position, of a carrier adapted to be removably connected with said carriage by said platen securing means and comprising in combination as a unit a rotatable platen adapted to coact with said guide means, means for supporting a strip of transfer material at one side of the platen, means for rotating the platen to feed the work sheets to writing position, a separator at one side of the platen arranged to direct the work sheets to opposite sides of the transfer material, and means for feeding the transfer material in a direction transverse to the direction of feed of the work sheets.
- 45 9. In a manifolding attachment for writing machines having a reciprocating mechanism and means to removably connect a platen with said reciprocating mechanism, a carrier adapted to be removably connected with said reciprocating mechanism, and comprising in combination as a unit, a platen, means for holding one or more strips of transfer material transversely to the direction of rotation of the platen, and a separating and guiding means arranged to di-

rect work-sheets to the opposite sides of the transfer material.

10. In a manifolding attachment for writing machines having a reciprocating mechanism and means to removably connect a platen with said reciprocating mechanism, a carrier adapted to be removably connected with said reciprocating mechanism by said platen connecting means and comprising in combination as a unit, a rotatable platen, means for holding one or more strips of transfer material transversely to the direction of rotation of the platen, and a separating and guiding means arranged to direct work-sheets to the opposite sides of the transfer material.

11. In a manifolding attachment for writing machines having a reciprocating mechanism and means to removably connect a platen with said reciprocating mechanism, a carrier adapted to be removably connected with said reciprocating mechanism, and comprising in combination as a unit, a rotatable platen, means for carrying one or more strips of transfer material transversely to the direction of rotation of the platen, and a separating and guiding means arranged to guide work-sheets into a copying relation with the said transfer material.

12. In a manifolding attachment for writing machines having a reciprocating mechanism and means to removably connect a platen with said reciprocating mechanism, a carrier adapted to be removably connected with said reciprocating mechanism and comprising in combination as a unit, a rotatable platen, means for carrying a strip of transfer material and feeding the same transversely to the direction of rotation of said platen, and a separating and guiding means extending longitudinally throughout substantially the length of the writing line of the typewriter and downwardly from a point above the lower edge of the transfer material but below the said writing line, said means arranged to direct work-sheets into a copying relation with the said transfer material.

In testimony whereof I affix my signature.

CLIFFORD W. MARSH.
